TUBE REDUCING MEANS

James Robert Coe, Waterbury, Conn., assignor to
 The American Brass Company, Waterbury,
 Conn., a corporation of Connecticut

Application February 19, 1931, Serial No. 516,905

47 Claims. (Cl. 80—14)

This invention has for an object the provision of a novel and improved apparatus for accomplishing expeditiously and effectively reduction in cross sectional area of metal tubes. The invention comprises new and improved means for feeding metal tube stock, step by step, to bring successive increments thereof into the range of action of elements for reducing the cross sectional area of the tube stock and elongating the same. A further feature of the invention resides in the provision of novel means whereby rotation of the tube stock is effected concurrently with the forward step by step feeding thereof, such rotation of the stock enabling the reducing elements on their ensuing reducing stroke to iron out fins developed on the stock during the preceding reducing stroke of said elements. The invention further comprises novel and effective means whereby tube blanks may be readily loaded into the apparatus. These and other features will be best understood from the ensuing description of a specific embodiment of the invention, and will be further pointed out in the claims hereto appended.

2. In the accompanying drawings:

Fig. 1 is a plan view of a portion of a tube-reducing machine embodying my invention.

Fig. 1a is a plan view constituting a continuation of Fig. 1 and showing the remaining portion of said machine.

Fig. 2 is a side elevation of the portion of the machine shown in Fig. 1.

Fig. 2a is a side elevation of the portion of the machine shown in Fig. 1a.

Fig. 3 is a view in elevation, partly in vertical section, at the rear of the machine.

Fig. 4 is a fragmentary vertical longitudinal section on line 4—4 of Fig. 3.

Fig. 5 is a transverse vertical section on line 5—5 of Fig. 2.

Fig. 6 is a transverse vertical section on line 6—6 of Fig. 2.

Fig. 7 is a vertical sectional detail view of a clamping mechanism for engaging a tube blank at certain times.

Fig. 8 is a view partly in elevation and partly in vertical section on line 8—8 of Fig. 1.

Fig. 9 is a view in horizontal section on line 9—9 of Fig. 6.

Fig. 10 is a view in transverse vertical section on line 10—10 of Fig. 1a.

Fig. 11 is a view in longitudinal vertical section on line 11—11 of Fig. 10.

Fig. 12 is a detail view showing a rack and gear whereby the tube-reducing rolls are driven.

Fig. 13 is a fragmentary detail view of a portion of tube stock illustrating the effect produced thereon by reducing elements embodying a feature of my invention.

Referring to the drawings the machine is 60 mounted upon a suitable supporting frame or base designated generally as A. Mounted for reciprocation on said base is a carriage 2 which conveniently may comprise a pair of spaced side frames 3, 3, suitably secured to each other as by 65 bolts 4. Positioned between said side frames are oscillatory rolls 6, 6', the shafts 7, 7' (Fig. 10) of which are journaled in anti-friction units 8 in the carriage side frames. Said rolls have grooves 9, 9' respectively, in their peripheries for acting 70 upon and reducing the cross sectional area of the tube stock as will be noted more particularly hereinafter. Each of the anti-friction units may comprise a housing or container 3' in which the anti-friction elements of the unit are mounted, 75 and whereby the unit may be readily positioned in one or the other of the side frames. Plates 10, 10' on each side frame cover the respective units therein.

Suitably mounted on the carriage, as through 80 one of the bolts 4, are rollers 11, 11, which rollers engage tracks 12, 12, secured to the base A. The carriage further comprises extensions 13, 13, projecting forwardly from the frames 3, 3, and integral therewith. Through said extensions passes 85 a crosshead rod 14 on opposite ends of which are rollers 15, 15. Secured to base A adjacent the carriage 2 and on opposite sides thereof are vertical frames 16, 16 each provided with a trackway 17 as shown in the frame 16 appearing in 90 Fig. 10. The rollers 15, 15 rest upon the trackways 17 in the respective frames 16, 16 and also engage the under sides of plates 18, 18 secured to the tops of said frames and overlying the trackways 17 thereof. It will thus be seen that through 95 its rollers 11, 11, and 15, 15 and the cooperating trackways the carriage 2 is freely reciprocable upon the bed or base A. For reciprocating the carriage I have shown crank arms 19, 19 journaled on the crosshead rod 14 and connected to crank 100 shaft 20. The latter is journaled in bearings in the base A and has secured thereto a gear 21 which meshes with a pinion 22 fastened to a shaft 23 also rotatable in bearings on said base. Shaft 23 is operable by a motor 24 through 105 a clutch 25 of conventional type and operable in any suitable or well-known way either to establish or to disestablish a connection between said motor and said shaft. It will thus be apparent that when the shaft 23 is in operation the carriage 110

2 will be given a complete reciprocation for each revolution of the crank shaft 20.

The roll shaft 7 has secured thereto a pinion 26 which meshes with a rack 27 fastened to an upwardly extending frame or standard 28 (Fig. 10) on the base A. Keyed to the hub 26' of said pinion is a gear 29 which meshes with a gear 30 fastened on the roll shaft 7'. It will thus be seen that during the operation of the carriage 2 the rolls 6, 6' carried thereby are automatically rotated, each being turned in a direction opposite to that of the other. During the forward stroke of the carriage the roll 6 will be turned in one direction by the rack 27 and connections while during the return stroke of said carriage said roll will be turned in the reverse direction; while the roll 6' will during each stroke rotate oppositely to the direction of rotation of roll 6. The rolls 6, 6' need not make a complete rotation during either stroke of the carriage, but their movement may instead be oscillatory, so that each roll turns first in one direction through a portion of a revolution during the forward stroke and then returns to its original position during the rearward or return stroke. It will thus be apparent that while I have shown the elements 6, 6' in the form of rollers they might instead be simply segmental rocker elements. While in the particular embodiment here shown, the rolls are not turned through a complete revolution by the travel of the carriage through a complete stroke, it will be apparent that the parts may be so designed that the rolls make a complete, or any desired incomplete, rotation for each stroke of the carriage; the extent of rotation of the rolls in each carriage stroke depending upon the relation of the circumference of the rolls to the extent of the stroke.

Secured to the base A rearwardly of the rolls 6, 6' and carriage 2 is a frame 31 for supporting tube blanks 32; said frame comprising vertically extending standards 33 and beams 34 secured to said standards and extending in a direction transverse to the machine. The beams 34 are inclined as shown in Fig. 5 so that the blanks roll downwardly thereon by gravity toward the central longitudinal vertical plane of the machine; the lowermost or innermost blank 32 being received in the notched portions 35 of a pair of lifting bars 36 mounted to slide vertically in standards 37. The bars 35 are connected to rock arms 38 fastened to a rock shaft 39 which is connected through an arm 40 and link 41 (Fig. 5) with the rod 42 of a piston 43 movable in a fluid pressure cylinder 44. Air or other fluid pressure may be supplied to said cylinder through a pipe 45 controlled by a suitable valve which in one position establishes communication between a source of fluid pressure and the cylinder 44 and in another position cuts off such communication and establishes communication between said cylinder and the atmosphere. Such valves being well known, illustration thereof is unnecessary. It suffices to note that upon the admission of pressure through pipe 45 into casing 44 the piston 43 is raised, whereby, through shaft 39 and rock arms 38 the bars 36 are elevated. The tube blank 32 engaged by said bars is thereby raised into the path of a tubular extension 46 which projects forwardly from a cross-head 47 mounted to travel on and having threaded engagement with a pair of threaded shafts or feed screws 48, 49. By rotation of said screws as hereinafter described, the cross-head extension 46 is caused to push forwardly the tube blank 32 which has been raised into its path and to bring said blank into en-

gagement with the interior of a bushing 50 journaled in a frame 51 on a portion of the bed or base A, through which bushing the tube blank is fed by said cross-head into position between the reducing rolls 6, 6'. After the tube blank has been placed under the control of the cross-head 47 and engaged with the bushing 50, the fluid pressure beneath the piston 43 may be vented to the atmosphere by manipulation of the valve above referred to, whereupon the bars 36 descend into position for receiving another of the tube blanks on said beams 34. It may be noted that the bars 36, during their movement to and from position for placing a blank under control of the cross-head, engage the succeeding blank on the beams 34 and thereby prevent the blanks on said beams from rolling off the same. When in their lowermost position the notched upper portions 35 of said bars 36 are in position for receiving the adjacent tube blank for elevating the latter when fluid pressure is next admitted to cylinder 44.

The feed screws 48, 49 are journaled for rotation at their front ends in bearings 51', 51' in the frame 51 and at their rear ends in bearings 52', 52' in a frame 52 secured to the rear end of the base A. Said shafts 48, 49, have secured thereto, adjacent the rear ends thereof, gears 53, 54, respectively, which mesh with an intermediate gear 55 the hub 55' of which (Fig. 4) is journaled for rotation in the frame 52. Gear 55 meshes with a gear 56 secured to a shaft 57 which is rotatably mounted in bearings 57', 57' in said frame 52. Fastened to said shaft 57 so as to rotate with said shaft and the gear 56 is a ratchet wheel 58. The latter is engaged by a pawl 59 carried by cross bar 60 slidably mounted in a transverse channel 61 in the frame 52. At one end the bar 60 carries a roller 62 which is engaged by a cam 63 on a shaft 64. The latter extends longitudinally of the machine and is driven by the crank shaft 20 through the bevel pinions 65, 66 (Fig. 1A); the shaft 64 and cam 63 making one revolution for each revolution of the crank shaft. At its other end the bar 60 is connected to a piston 67 slidable in fluid pressure cylinder 68. Movement of the rod 60 by the cam 63 may be opposed by the action of fluid pressure behind the piston in the chamber 68. During each rotation of the shaft 64 the cam 63 acts upon rod 60 and shifts the latter against the pressure behind the piston 67, to bring pawl 59 into engagement with the next tooth on the ratchet wheel 58; and, as the rotation of shaft 64 continues, the high point of the cam 63 passes out of engagement with roller 62, whereupon the pressure behind piston 67 returns the rod into engagement with the low point of the cam, the ratchet wheel 58 being turned one step by pawl 59 during said return movement of rod 60. Thus in each rotation of the shaft 64 the rod 60 is operated, first to engage pawl 59 with the succeeding tooth on ratchet 58 and then to turn said ratchet one step and thereby, through gears 56, 55, 54, and 53, to rotate the screws 48, 49 and feed the cross-head 47 and tube 32 forwardly one step.

During regular operation pressure air is constantly supplied to the rear end of cylinder 68 through pipe 69. When it is desired to discontinue feeding of the tube, the air at the back of the piston 67 is cut off from the supply source and vented to the atmosphere by turning of a suitable valve and air is admitted through pipe 70 to the front of chamber 68 by turning of a suitable valve connected to said pipe. The piston 150

67 is now moved into the rear of the cylinder 68 and retracts the rod 60 so that the latter is removed from the range of action of the cam 63 and the pawl 59 is disengaged from ratchet wheel 58. The cross-head 47 may now be retracted to permit the introduction of a new tube blank, such retraction being readily accomplished at comparatively rapid speed by energizing an electric motor 71 which is connected through pinion 72 with gear 56 for driving the latter. Restoration of rod 60 into position for operation by cam 63 and for acting upon ratchet 58 may be accomplished by placing pipe 70 in communication with the atmosphere through turning of its controlling valve and placing pipe 69 in communication with the fluid pressure source.

Extending through the cross-head 47 and the tube 32, and between the rolls 6, 6', is a mandrel 73 for supporting the inside wall of the tube during the rolling and ironing operations, regulating the inner form of the tube during rolling and controlling the inside diameter of the finished tube. The forward end 73' of said mandrel is preferably tapered to facilitate feeding forward of the tube. The rear portion of said mandrel projects, as shown in Fig. 4, through a sleeve 74 which extends through gear 55 and is splined thereto so as to be compelled to rotate with said gear but at the same time to be movable longitudinally with respect thereto. The mandrel further projects rearwardly through a sleeve 75 rotatably mounted in a cross-head 76. The latter is supported slidably upon a pair of rods 77, 78, which at their forward ends are mounted in brackets 80 on the frame 52 and at their rear ends are mounted in bracket portions 81 of a frame 82. Adjacent its rear end the mandrel 73 is squared as indicated at 73'' and extends through a correspondingly shaped hole in a plate 83 which is secured to the rotatable sleeve 75. Said sleeve 74 also has secured upon the front end thereof a sleeve 84 having clutch teeth 85 engageable with corresponding clutch teeth on the head 74' of sleeve 74. Normally, a spring 86 maintains sleeve 74 pressed rearwardly with its teeth in engagement with those of sleeve 84. Forward movement of the mandrel with respect to the cross-head 76 is limited by the engagement with plate 83 of a washer 87 held in place against the end of squared portion 73'' of said mandrel by nut 88 threaded on the end of said shaft.

The mandrel 73 is movable either to a forward position wherein it projects between the rolls 6, 6' or to a rearward position wherein it permits a new tube blank to be inserted by the lifting mechanism between the cross-head extension 46 and the bushing 50. The position of the mandrel is controlled by a piston 89 (Fig. 8) in a cylinder 90, the rod 91 of which piston is connected to cross-head 76 through bracket 92 secured to said cross-head. Pipes 93, 94 connectable to a fluid pressure source through suitable valves communicate with the front and rear ends respectively of the cylinder 90, and it will be apparent that the mandrel 73 may be retracted by admitting fluid pressure through pipe 93 to the front of the cylinder 90, and at the same time venting the rear of the cylinder to the atmosphere through pipe 94. Conversely, the mandrel 73 may be moved to its forward position by admitting fluid pressure to the rear of the cylinder 90 through pipe 94 and venting the front of said cylinder to the atmosphere through pipe 93.

When the mandrel is in its forward position the teeth on the clutch members 74', 84 are in

engagement with each other, and operation of the gear 55 to advance the tube is accompanied by rotation of the mandrel through 90°. The portion of the tube at the forward end of the mandrel engages the latter with sufficient tightness 80 that the tube is rotated by turning of the mandrel; such rotation of the tube being further assisted by rotation of the bushing 50, which fits the tube sufficiently tightly to impart rotation thereto. It will be apparent that whenever gear 55 is rotated, the sleeve 74 and clutch member 74' turn also so that, as long as the mandrel is in its normal or forward position, the rotation of said gear 55 is transmitted to clutch member 84 and thence through sleeve 75 and plate 83, to the mandrel. At the same time the bushing 50 is turned through a gear 95 on screw 48, which gear meshes with a gear 96 on said bushing. The extent of rotation imparted by gear 55 to the mandrel 73 and bushing 50 in each actuation of the gear by pawl 59, ratchet 58, and gear 56 is 90°; and thus the tube 32 is turned about the longitudinal axis through one-fourth of a revolution in each step of forward feeding of said tube when the mandrel is in its normal position.

When a tube blank is in position between the rolls 6, 6' and the machine is set in operation, the carriage 2 is moved first forwardly and then backwardly in each revolution of the crank shaft, 105 and during said forward movement the rolls 6, 6' act upon the tube, squeezing the associated portion of the tube stock forwardly on the mandrel and reducing the cross sectional area of said portion. The grooves 9, 9' in the respective rolls, as indicated in Fig. 10, are of tapered formation throughout the greater part of their length; the portions of said grooves that surround the tube at the commencement of the forward travel of the carriage, and during the initial portion of said travel, being of such size 110 as to provide clearance between the rolls and the tube, as indicated by the left hand dotted line position of the rolls shown diagrammatically in Fig. 13, so that the latter may be freely rotated and advanced as described hereinbefore. The portions of the grooves 9, 9' which engage the tube as the forward movement of the carriage continues are of such progressively decreasing size that during the greater portion of the forward travel of the carriage the rolls act upon the tube to reduce the cross sectional area thereof. The portions of the grooves which engage the tube during the final portion of the forward travel of the carriage are of uniform cross section 115 corresponding to the reduced cross section of the tube and acting to iron or smooth the tube following reduction thereof by the tapered portion of the grooves. The grooves 9, 9' may be so designed, for example, that, assuming the stroke 120 of the carriage to be sixteen inches, the rolls turn idly with respect to the tube for the first four inches of said stroke, then the rolls act upon the tube to reduce the area of the latter during the ensuing ten inches of stroke, and finally the concentric or uniform reduced portions 125 of the grooves act upon the tube to iron or smooth the latter during the remaining two inches of said stroke. During the return or rearward travel of the carriage, the concentric reduced portions of the grooves continue their ironing or smoothing action for the first two inches of said stroke, while during the remainder of said stroke the rolls turn idly with respect to 130 the tube. The foregoing figures are of course 135 140 145 150

illustrative merely and may obviously be varied. As has been noted, the tube is automatically fed forward one step and is concurrently rotated through 90° in each rotation of the crank shaft, and prior to the commencement of the reducing action of the rolls on the tube. This turning and feeding of the tube may take place entirely during the initial portion of the forward travel of the carriage (four inches in the example above indicated), or during the return stroke, or may be carried out partly during the last portion of the return stroke and completed in the initial portion of the forward stroke, the time during which said feed and turning of the tube take place being readily determinable by suitable design of the cam 63.

The shape of the tapered portions of the grooves 9, 9' that effect reduction in the area of the tube stock is preferably such as to produce the greatest reduction during the first part of the reducing portion of the carriage stroke.

This may be accomplished by designing said grooves so that the portions thereof that act upon the tube during the first part of the reducing portion of the carriage stroke have a pronouncedly greater degree of taper than those portions of said grooves that act upon the tube during the balance of the reducing portion of said stroke. Reference in this connection may be made to Fig. 13 wherein there is illustrated the effect produced during the reducing portion of the carriage travel by rolls having grooves of varying taper such as above referred to. In this view, the lines designated *a*, *b*, indicate the beginning and end of the reducing portion of the stroke or travel of the carriage, while the lines *b*, *c* define the beginning and end of the smoothing portion of said stroke. The portion of the tube between the lines *a'*, *b'* is that portion which occupied the reducing zone *a*, *b* in the preceding forward stroke of the carriage, while portion *b'*, *c'* formerly occupied the smoothing zone *b*, *c*; said tube having in the meantime been fed forward the increment represented by the distance *a*, *a'*, ready for the next forward stroke of the carriage and reducing rolls. During said next forward stroke, the portion of the tube between the lines *a*, *b* will be reduced to the form indicated by the dot-dash lines *d*, *d*. From this the effect produced by rolls having grooves of varying taper as above noted will readily be seen. By having the greater reduction occur during the initial part of the reducing portion of the carriage stroke, increased efficiency is attained; since it has been found that the tube during this portion of the stroke offers less resistance to reduction than during the ensuing portion of the stroke wherein the wall of the tube has become thinner and the metal has become harder through working. In short, the grooves 9, 9' are preferably designed to effect reduction at a varying rate during the reducing portion of the carriage stroke, this rate being greater during the first part thereof and less during the remaining part of said reducing portion of the stroke.

To provide for a true rolling movement, without slippage, of each roll upon the tube stock notwithstanding the engagement of the roll with the stock at different distances from its axis of rotation due to varying depth of its groove 9 or 9', I mount the pinion 26 eccentrically to the axis of shaft 7 and provide a rack 27 of suitable configuration to cooperate with the eccentrically mounted pinion throughout the stroke of the carriage as indicated in Fig. 12. By such eccentric

mounting of the pinion and said corresponding configuration of the rack the rolls are driven at such rate during the travel of the carriage that a true rolling action of the rolls upon the stock may be attained and slippage obviated.

Briefly summarizing, it will readily be seen that when the mandrel 73 is in its forward position and the machine is in operation the portion of the tube stock in the range of action of the grooved rolls 6, 6' is engaged by said rolls during the forward travel of the carriage with the result that said portion of the tube is reduced in cross section, and is at the same time elongated and forced forwardly over said mandrel, said portion being furthermore subjected to a smoothing or ironing action during the final portion of the forward stroke of said carriage. During the initial part of the return stroke of the carriage the smoothing or ironing action of the rolls is continued, and during the last portion of the return stroke and the first portion of the ensuing forward stroke the enlarged or clearance portions of the grooves 9, 9' are opposite the tube stock so that the stock can be readily moved forward one step and simultaneously rotated through 90° by the operation of gear 56 through pawl 59 and ratchet 58. As has been noted, such operation of the gear 56 turns the screws 48, 49, whereby the cross-head 47 is forced forwardly one step to feed a new increment of the stock into the range of action of the rolls; and at the same time the rotation of gear 55, acting through clutch members 74', 84, sleeve 75, and plate 83, rotates the mandrel through 90° and thereby turns the tube stock through a quarter of a revolution, this turning of the tube stock being further assisted by rotation of bushing 50 in conjunction with the turning of screw 48. Due to said rotation of the tube stock through 90° the fins formed on the tube stock as a result of the reducing action of the rolls during the previous forward stroke of the carriage are ironed out by said rolls on the ensuing forward stroke, and the rolls additionally act upon the new increment of stock to effect reduction thereof.

For guiding the finished tube as the latter emerges from the rolls 6, 6', I provide on the carriage 2 a housing 97 having an enlarged head 98 through which passes the cross-head rod 14. Said rod has a transverse passage 99 therethrough communicating with the interior of the housing 97. The rearward end of the housing may be supported on the carriage in any suitable way, as through a bracket 100, and, as shown, extends adjacent the rolls 6, 6' for receiving the finished tubing as the latter leaves the rolls. At its rear end the housing 97 is in threaded engagement with a tube 101 which extends rearwardly through bearings 102, 103 supported from the base of the machine. The housing 97 and tube 101 guide the finished tubing and prevent deflection of the latter into the path of moving parts. If desired, there may be positioned at different points in the housing 97 a series of anti-friction bearings, such as indicated at 104, 140 for engaging the finished tubing and holding it in a central position, and providing frictionless supports for the finished tubing so that a decreased resistance is offered to turning of the tube stock by rotation of the mandrel.

To further facilitate turning of the mandrel and tube stock, the member 46, which projects forwardly from cross-head 47 and through which said mandrel extends is shown mounted in anti-friction bearings in said cross-head. Thus, as

- shown in Fig. 4, the rearwardly extending portion 46' of said member 46 is mounted in cross-head 47 through the medium of anti-friction bearing units 105.
- 5 When a new tube blank 32 is to be loaded into the machine the cross-head 47 is retracted and the mandrel 73 is withdrawn rearwardly sufficiently to permit the new blank to be inserted between the member 46 and bushing 50. Means 10 are provided in this connection for clamping the preceding tube blank to facilitate withdrawal of the mandrel therefrom. This means comprises a pair of clamping jaws 106, 106 positioned at the forward end of the bushing 50 and pivotally 15 mounted on bolts 107, 107, projecting from the frame 51. A plate 108, mounted on the frame 51 by said bolts 107 and by another bolt 109, serves to maintain said jaws in proper relation to said frame and to the tube blank projecting 20 from bushing 50. At their upper ends the respective jaws 106 are connected through links 110 to the rod 111 of a piston 112 mounted in a chamber or cylinder 113. The latter may conveniently be formed as part of a frame 114 secured 25 to base 115 projecting upwardly from frame 51. Air pressure from a suitable source may be admitted into chamber 113 either above or below piston 112 through pipes 116, 117, respectively.
- 30 For loading a new tube blank into the machine the operation of the latter is stopped while the preceding tube blank is still in position for engagement by the clamping jaws 106 and is supported by bushing 50. Air pressure is then admitted through pipe 116 into chamber 113 by manipulation of a suitable valve, pipe 117 being simultaneously vented to the atmosphere, whereupon the piston 112 descends and, through links 110, forces the jaws 106 into firm engagement 35 with said tube blank 32 that is supported in the bushing 50. Air pressure is next admitted through pipe 93 into chamber 90, whereby piston 89 is operated to retract the mandrel to such position as will permit a new tube to be interposed between the front end of said mandrel and the rear end of the bushing 50. Air pressure is also admitted through pipe 70 into chamber 68, and the piston 67 is thereby operated to disengage pawl 59 from ratchet 58. The motor 71 is 40 then set in operation to turn gears 56 and 55 rapidly in the direction the reverse of that in which they are actuated when pawl 59 is in operation, until the cross-head 47 is retracted sufficiently to permit the interposition of a tube blank between the rear end of bushing 50 and the forward end of the projecting member 46. For conveniently controlling the motor 71, a switch arm 118 may be mounted on a pedestal 119 adjacent said motor, as shown in Fig. 2.
- 45 With the parts in the position aforesaid, air pressure is admitted through pipe 45 into chamber 44, whereby piston 43 is raised and elevates the lifter bars 36, which carry upwardly from the beams 34 the tube blank 32 engaged by the jaws 55 of said lifter bars, and bring said new tube blank between the aforesaid projecting member 46 and bushing 50. By then admitting pressure to the rearward side of piston 89 the mandrel is projected through the aforesaid new tube blank as well as through the previously inserted tube and thence into its normal or forward position. The clamping jaws are then released by restoration of piston 112 to its upper position. The pawl 59 may now be restored into engagement with ratchet 58 by admission of pressure to piston 67
- through pipe 69; and upon then setting the machine in operation the cross-head 47 is fed forwardly, pushing the new tube blank into the bushing 50 and bringing the forward end of said blank into engagement with the rear end of the previously inserted tube, whereupon as the operation of the machine continues feeding of said previously inserted tube through the rolls 6, 6' is resumed, and the newly inserted blank is thence subjected to the action of said rolls, the operation being again stopped when said newly inserted blank is about to leave the bushing 50. In the meantime following the entrance of the forward end of said newly inserted blank into the bushing 50, the lifting bars 36 may be lowered as the result of venting of the pressure below the piston 43.
- 50 It has been noted that the sleeve 74, while compelled to rotate with gear 55, is slidably longitudinally with respect thereto. The spring 86, interposed between gear 55 and the head 74' of said sleeve, as shown, urges said sleeve rearwardly. When the mandrel 73 is retracted the clutch teeth of the sleeve 84 are disengaged from those of sleeve 74; rearward movement of sleeve 74 being limited by engagement of a nut 121 threaded on the end of said sleeve with the forward end of hub 55' of gear 55. The retraction of the mandrel as aforesaid and consequent disengagement of said clutch teeth enable the gear 55 and connected elements to be freely rotated by motor 71 to retract the cross-head 47 as previously described. If upon return of the mandrel into its forward position, following rotation of gear 55 and sleeve 74 with respect to sleeve 84, the teeth of 55 said member 84 do not mesh properly with those of sleeve 74, the latter simply moves rearwardly, compressing spring 86; and as soon as gear 55 is again revolved the spring 86 reacts and forces said sleeve 74 rearwardly so that its teeth are properly engaged with those of member 84.
- 55 It will be noted that the means which I have provided for driving the tube feeding and rotating mechanism is flexible in its action. Thus, the rod 60, which through pawl 59 actuates the tube 120 feeding and rotating elements, is not driven positively to effect feeding and turning of the tube, but instead is positively actuated simply to compress the air or other pressure medium in cylinder 68 and is then operated by said compressed 125 pressure medium to actuate the ratchet wheel 58 and thereby feed and rotate the tube. In mechanisms wherein the tube feeding and turning mechanism is positively driven overloading of such mechanism (as by accidental overfeeding of 130 the tube, resulting in excessive fin, or by freezing of the tube on the mandrel as may occur occasionally) is likely to cause breakage of parts. By my arrangement, wherein the shaft 20 does not positively drive the tube feeding and rotating means 135 but instead acts to compress a yieldable pressure medium during the major part of each revolution of said shaft and to release said medium for effecting operation of the tube feeding and driving mechanism at a predetermined point in the revolution, the danger of breakage or smashing of parts in the event of overload is eliminated; since if the load exceeds the capacity of the pressure medium in cylinder 68, the rod 60 and pawl 59 will not be operated. In lieu of air any other 140 suitable pressure medium, such as a compression spring, may, of course, be interposed between piston 67 and the rear end of the cylinder 68.
- 56 It may be additionally noted that a new tube blank may be readily and expeditiously loaded 145

into the machine without stopping rotation of the crank shaft 20 or reciprocation of the carriage 2; thereby saving time. Thus, when a new tube is to be inserted, the tube feeding and turning mechanism is thrown out of action by the admission of air to the front end of cylinder 68 through pipe 70; and the previously inserted tube securely clamped as the result of the admission of air to clamping cylinder 113 through pipe 116, wherefore by said tube is not only held against retraction during withdrawal of the mandrel 73 but is also positively prevented from being carried back and forth by the reciprocation of the carriage 2 and its rolls 6, 6'. It will thus be evident that the insertion of a new tube does not require stoppage of the operation of the shaft 20 or carriage 2. The clutch 25 may, if desired, be omitted between shaft 23 and motor 24, and a flexible coupling of standard or conventional type may be interposed between the motor 24 and shaft 23.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

I claim:

- 30 1. In a tube reducing apparatus, a rotatable member for receiving a tube, a reciprocable carriage, means for reciprocating said carriage along the tube, tube-reducing elements mounted on said carriage, a mandrel extending into said tube, and means correlated with said reciprocating means for concurrently rotating said member and said mandrel for effecting rotation of the tube.
- 40 2. In a tube reducing apparatus, a rotatable member for receiving a tube, a reciprocable carriage, means for reciprocating said carriage along the tube, tube reducing elements mounted on said carriage, a mandrel extending into said tube, means correlated with said reciprocating means for feeding the tube longitudinally, and means controlled by said feeding means for rotating said mandrel and said member to effect rotation of the tube concurrently with the feeding thereof.
- 50 3. In a tube reducing apparatus, a mandrel adapted to have a tube positioned thereon, a reciprocable carriage, means for reciprocating said carriage along the tube, tube reducing elements mounted on said carriage, a member for feeding the tube forwardly, means correlated with said reciprocating means for shifting said member forwardly step-by-step during successive reciprocations of said carriage, and means other than said member controlled by said shifting means for rotating said mandrel to effect rotation of said tube concurrently with the feeding thereof.
- 60 4. In a tube reducing apparatus, a mandrel on which a tube is positioned, a reciprocable carriage, means for reciprocating said carriage along the tube, tube reducing elements mounted on said carriage, a member for feeding the tube forwardly, means correlated with said reciprocating means for shifting said member forwardly step-by-step during successive reciprocations of said carriage, means controlled by said shifting means for rotating said mandrel to effect rotation of said tube, means for retracting said mandrel to permit the insertion of a new tube, and connections controlled by said mandrel retracting means for temporarily rendering inoperative said mandrel rotating means.

5. In a tube reducing apparatus, a mandrel adapted to have a tube positioned thereon, a reciprocable carriage, means for reciprocating said carriage along the tube, tube reducing elements mounted on said carriage, a member for feeding the tube forwardly, screw means for actuating said member, means preventing movement of said mandrel forwardly with said member, and means correlated with said reciprocating means for causing said screw means to shift said member forwardly step-by-step during successive reciprocations of the carriage.

6. In a tube reducing apparatus, a reciprocable carriage, reducing elements mounted on said carriage and adapted to receive a tube therebetween, means for reciprocating said carriage along the tube, a member positioned behind the tube for pushing the tube forwardly with respect to the mandrel and into operative relation with said reducing elements, a mandrel extending through opposite ends of said member and into said tube, and means correlated with said reciprocating means for shifting said member forwardly step-by-step in successive reciprocations of the carriage.

7. In a tube reducing apparatus, a reciprocable carriage, reducing elements mounted on said carriage and adapted to receive a tube therebetween, means for reciprocating said carriage along the tube, a pair of screw members, a crosshead mounted on said screw members behind the tube for pushing the tube forwardly, and means correlated with said reciprocating means for causing said screw members to shift said crosshead forwardly step-by-step in successive reciprocations of the carriage.

8. In a tube reducing apparatus, a reciprocable carriage, reducing elements mounted on said carriage and engageable with a tube, means for reciprocating said carriage along the tube, a member positioned behind the tube for pushing the tube forwardly, a mandrel extending through said member and into said tube, means preventing said mandrel from moving forwardly with said members, means correlated with said reciprocating means for shifting said member forwardly step-by-step in successive reciprocations of the carriage, and means controlled by said shifting means for rotating said mandrel to effect rotation of said tube.

9. In a tube reducing apparatus, a reciprocable carriage, reducing elements mounted on said carriage and engageable with a tube, means for reciprocating said carriage along the tube, a pair of screw members, a crosshead mounted on said screw members behind the tube for pushing the tube forwardly, means correlated with said reciprocating means for causing said screw members to shift said crosshead forwardly step-by-step in successive reciprocations of the carriage, and means controlled by said reciprocating means for rotating the tube.

10. In a tube reducing apparatus, a reciprocable carriage, reducing elements mounted on said carriage and engageable with a tube, means for reciprocating said carriage along the tube, a member positioned behind the tube for pushing the tube forwardly while the mandrel remains stationary, a mandrel extending through opposite ends of said member and into said tube, means correlated with said reciprocating means for shifting said member forwardly step-by-step in successive reciprocations of the carriage, and means controlled by said reciprocating means for

- rotating said mandrel to effect rotation of said tube.
11. In a tube reducing apparatus, a reciprocal carriage, reducing elements mounted on said carriage and engageable with a tube, means for reciprocating said carriage along the tube, means including a mandrel for supporting the tube and a member for feeding the tube forwardly along the mandrel, screw means separate from said member for actuating said member, means correlated with said reciprocating means for causing said screw means to shift said member forwardly step-by-step in successive reciprocations of the carriage, and means causing said screw means to retract said member with a continuous movement to permit the introduction of a new tube. 80
12. In a tube reducing apparatus, a mandrel on which a tube is positioned, reducing elements engageable with the tube, a member for feeding the tube forwardly, means for shifting said member forwardly step-by-step relatively to said mandrel to bring successive increments of the tube into the range of action of said elements, means for throwing said step-by-step shifting means out of action, and means for retracting said member with a continuous movement preliminarily to the introduction of a new tube. 90
13. In a tube reducing apparatus, a reciprocal carriage, reducing elements mounted on said carriage and engageable with a tube, means for reciprocating said carriage along the tube, a member for feeding the tube forwardly, screw means for actuating said member, a rotatable supporting element for the tube, means correlated with said reciprocating means for causing said screw means to shift said member forwardly step-by-step in successive reciprocations of the carriage, and means connecting said screw means and said rotatable element for imparting rotation to the latter and thereby to the tube concurrently with the step-by-step shifting of said tube feeding member. 100
14. In a tube reducing apparatus, a reciprocal carriage, reducing elements mounted on said carriage and engageable with a tube, means for reciprocating said carriage along the tube, a member positioned behind the tube for pushing the latter forwardly, means correlated with said reciprocating means for shifting said tube-feeding member forwardly step-by-step in successive reciprocations of the carriage, means between said carriage and said member for supporting the tube during its forward travel, means providing for retraction of said tube feeding member, and means adjacent said supporting means for bringing a new tube into position between said tube feeding member and said supporting means after said tube-feeding member has been retracted. 110
15. In a tube reducing apparatus, reducing elements engageable with a tube, means comprising a shiftable member engageable with the tube for feeding the tube step-by-step to bring successive increments thereof into the range of action of said elements, a mandrel extending into said tube, means for withdrawing the mandrel from the tube, means for retracting said shiftable member, and means for positioning a new tube forwardly of said mandrel and said shiftable member preparatory to bringing said tube into the range of action of said elements. 120
16. In a tube reducing apparatus, reducing elements engageable with a tube, means comprising a shiftable member engageable with a tube for feeding the tube step-by-step to bring successive increments thereof into the range of action of said elements, a mandrel extending into said tube, means for retracting said mandrel to permit introduction of a new tube into the machine, and clutch means whereby a connection is established between the mandrel and the tube feeding means for rotating the mandrel as an incident to feeding of the tube and whereby said connection is broken as an incident to retraction of said mandrel. 130
17. In a tube reducing apparatus, reducing elements engageable with a tube, a tube supporting member rearward of said elements, a tube feeding member movably mounted rearwardly of said tube supporting member for feeding the tube forwardly, tube clamping means adjacent the forward end of said tube supporting member, means for retracting said tube feeding member, and tube conveying means positioned for delivering a tube between said tube feeding member and said supporting member after said tube feeding member has been retracted. 140
18. In a tube reducing apparatus, reducing elements engageable with a tube, a member for supporting the tube in operative relation to said elements, means adjacent said supporting member for supporting a plurality of tubes, means for carrying a tube from the last mentioned supporting means and delivering said tube into position for engagement with said supporting member, means for shifting said delivered tube into engagement with said supporting member, and means to cause said carrying means to retract prior to continued advance of said shifting means. 150
19. In a tube reducing apparatus, reducing elements engageable with a tube, a member for supporting the tube in operative relation to said elements, downwardly inclined means supporting a plurality of tubes adjacent said supporting member, means for lifting a tube adapted when in lowered position to receive a tube from said downwardly inclined means and when in raised position to prevent the tubes on said downwardly inclined means from escaping therefrom, and means for raising said lifting means to bring the tube received when in its lowered position into position for engagement with said supporting member, and for retracting said lifting means at a subsequent time. 160
20. The method of inserting a new tube into a tube reducing machine prior to removal of a previously inserted tube therefrom, which comprises clamping said previously inserted tube, withdrawing a mandrel therefrom, retracting a tube feeding element, inserting a new tube forwardly of said mandrel and said tube feeding element, and projecting the mandrel forwardly through said new tube and into said previously inserted tube. 170
21. In a tube reducing machine, reducing elements engageable with a tube, means for feeding the tube into the range of action of said elements, a mandrel extending into said tube, means for retracting said mandrel to permit introduction of a new tube into the machine, and clutch means whereby a connection is established between the mandrel and the tube feeding means for rotating the mandrel as an incident to feeding of the tube and whereby said connection is broken as an incident to retraction of said mandrel. 180
22. In a tube reducing machine, reducing elements engageable with a tube, means for feeding

- the tube into the range of action of said elements, a mandrel extending into said tube, means for retracting said mandrel to permit introduction of a new tube into the machine, and means 5 whereby a connection is established between the mandrel and the tube feeding means for rotating the mandrel as an incident to feeding of the tube and whereby said connection is broken as an incident to retraction of said mandrel, said connection establishing means comprising a pair of clutch elements, one of which is engaged by a spring.
23. In a tube reducing machine, reducing elements for receiving a tube therebetween, means 15 for feeding a tube into the range of action of said elements, said means comprising a rotatable element, a mandrel extending into the tube, means for retracting said mandrel to permit introduction of a new tube into the machine, a clutch 20 member rotatable with said rotatable element but movable longitudinally with respect thereto, a second clutch member movable with the mandrel and being engageable with the first mentioned clutch member when the mandrel is in its forward position, connections from the second clutch member for producing rotation of the mandrel in response to rotation of the second clutch member by the first clutch member, and a spring urging 25 the first clutch member into engagement with the second clutch member.
24. In a tube reducing apparatus, a reciprocable carriage, reducing elements mounted on said carriage for receiving a tube therebetween, means for reciprocating said carriage along the tube, pressure means, means operated by said carriage-reciprocating means for storing energy in said pressure means, and means operated by said pressure means for feeding the tube longitudinally.
25. In a tube reducing apparatus, reducing elements for receiving a tube therebetween, means 40 for operating said elements to effect reduction of the tube, means for shifting the tube longitudinally to present successive increments thereof to the action of said elements, pressure means for actuating said shifting means, and means correlated with said operating means for storing energy in said pressure means.
26. In a tube reducing apparatus, reducing elements for receiving a tube therebetween, means 45 for operating said elements to effect reduction of the tube, means for shifting the tube longitudinally and rotating the same, pressure means for actuating said tube shifting and rotating means, and means correlated with said operating means for storing energy in said pressure means.
27. In a tube reducing apparatus, reducing elements for receiving a tube therebetween, means for operating said elements, means for shifting the tube longitudinally and rotating the same, pressure means for actuating said tube shifting and rotating means, and means correlated with said operating means for storing energy in said pressure means during a portion of the cycle of operation of said operating means and for releasing said pressure means to actuate said tube shifting and rotating means in another portion of said cycle.
28. In a tube reducing apparatus, reducing elements for receiving a tube therebetween, means 70 for operating said elements, means for shifting the tube longitudinally, pressure means for actuating said tube shifting means, and means correlated with said operating means for storing energy in said pressure means during a portion of the cycle of operation of said operating means and for releasing said pressure means to actuate said tube shifting and rotating means in another portion of said cycle.
29. In a tube reducing apparatus, reducing elements for receiving a tube therebetween, means for operating said elements, means for shifting the tube longitudinally, pressure means for actuating said tube shifting means in another portion of said cycle.
30. In a tube reducing apparatus, reducing elements for receiving a tube therebetween, means for operating said elements, pressure means, a member driven in one direction by said operating means for storing energy in said pressure means, and means operable upon movement of said member in the opposite direction under the influence of said pressure means for rotating said tube.
31. In a tube reducing apparatus, reducing elements for receiving a tube therebetween, means for operating said elements, pressure means, a member driven in one direction by said operating means for storing energy in said pressure means, and means operable upon movement of said member in the opposite direction under the influence of said pressure means for rotating said tube and shifting the same longitudinally.
32. In a tube reducing apparatus, reducing elements for receiving a tube therebetween, a carriage in which said elements are mounted, means for reciprocating said carriage along the tube, pressure means correlated with said reciprocating means, a member driven in one direction by said operating means for storing energy in said pressure means, and means operable upon movement of said member in the opposite direction under the influence of said pressure means for shifting said tube longitudinally.
33. In a tube reducing apparatus, reducing elements for receiving a tube therebetween, a carriage in which said elements are mounted, means for reciprocating said carriage along the tube, means for shifting the tube longitudinally, and flexible means correlated with said carriage reciprocating means for actuating said tube shifting means.
34. In a tube reducing apparatus, reducing elements for receiving a tube therebetween, a carriage in which said elements are mounted, means for reciprocating said carriage along the tube, means for shifting the tube longitudinally and rotating said tube, and flexible means correlated with said reciprocating means for actuating said tube shifting and rotating means.
35. In a tube reducing machine, a reciprocable carriage, reducing elements carried thereby for receiving a tube therebetween, means for reciprocating said carriage, means correlated with said reciprocating means for feeding the tube longitudinally, means for disconnecting said tube feeding means from the carriage reciprocating means when a new tube is to be inserted into the machine, and means for clamping the previously inserted tube to prevent longitudinal movement thereof by reciprocation of the carriage.
36. In a tube reducing machine, a mandrel adapted to have a tube positioned thereon, a reciprocable carriage, tube reducing elements on said carriage, means for reciprocating said carriage, means correlated with said reciprocating means for feeding the tube longitudinally, means for disconnecting said feeding means from the

- carriage reciprocating means when a new tube is to be introduced into the machine, and means for retracting the mandrel, and means for clamping the previously inserted tube to prevent longitudinal movement thereof by retraction of the mandrel or by reciprocation of the carriage. 37. The method of preparing for the introduction of a new tube into a tube reducing machine prior to removal of a previously inserted tube from operative relation to the reducing elements and notwithstanding continued reciprocation therein of a carriage on which the tube reducing elements are mounted, said method comprising clamping said previously inserted tube against movement by said reciprocation of the carriage, and withdrawing a mandrel from said previously inserted tube to permit the insertion of said new tube between said mandrel and said previously inserted tube. 38. The method of preparing for the introduction of a new tube into a tube reducing machine prior to removal of a previously inserted tube from operative relation to the reducing elements and notwithstanding continued reciprocation therein of a carriage on which the tube reducing elements are mounted, said method comprising throwing out of action a tube feeding mechanism and clamping said previously inserted tube against movement by said reciprocation of the carriage, and withdrawing a mandrel from said previously inserted tube to permit the insertion of said new tube between said mandrel and said previously inserted tube. 39. In a tube reducing apparatus, reducing means adapted to receive a tube, means for operating said reducing means, tube feeding means, fluid pressure means for actuating said tube feeding means, and means correlated with said operating means for storing energy in said fluid pressure means in one portion of the cycle of operation of said operating means and for releasing said fluid pressure means to actuate said tube feeding means in another portion of said cycle. 40. In a tube reducing apparatus, reducing means adapted to receive a tube, means for operating said reducing means, tube rotating means, fluid pressure means for actuating said tube rotating means, and means correlated with said operating means for storing energy in said fluid pressure means. 41. In a tube reducing apparatus a reciprocable carriage having reducing members adapted to receive a tube therebetween, a mandrel entering the tube and cooperating with the reducing members, and means for withdrawing the mandrel from a partially completed tube to enable a new tube to be introduced between the withdrawn mandrel and the partially completed tube and for returning the mandrel to its initial position. 42. In a tube reducing apparatus a reciprocable carriage having reducing members adapted to receive a tube therebetween, a mandrel entering the tube and cooperating with the reducing members, and fluid pressure means for withdrawing the mandrel from a partially completed tube to enable a new tube to be introduced between the withdrawn mandrel and the partially completed tube and for returning the mandrel to its initial position. to enable a new tube to be introduced between the withdrawn mandrel and the partially completed tube and for returning the mandrel to its initial position. 43. In a tube reducing apparatus a reciprocable carriage having reducing members engageable with a tube, a mandrel entering the tube and cooperating with the reducing members, means for withdrawing the mandrel from a partially completed tube to enable a new tube to be introduced between the withdrawn mandrel and the partially completed tube and for returning the mandrel to its initial position, and means for clamping the partially completed tube as a preliminary to withdrawal of the mandrel. 44. In a tube reducing apparatus, reducing members adapted to receive a tube therebetween, means for feeding said tube forwardly, a mandrel entering the tube and cooperating with the reducing members, means for withdrawing the mandrel from a partially completed tube to enable a new tube to be introduced between the withdrawn mandrel and the partially completed tube, and for returning the mandrel to its initial position, means maintaining the newly inserted tube in position between said mandrel and said partially completed tube while said mandrel is in its withdrawn position, and means for withdrawing said maintaining means. 45. In a tube reducing apparatus, reducing members adapted to receive a tube therebetween, means for feeding said tube forwardly, a mandrel entering the tube and cooperating with the reducing members, means for withdrawing the mandrel from a partially completed tube to enable a new tube to be introduced between the withdrawn mandrel and the partially completed tube, and for returning the mandrel to its initial position, and means holding said partially completed tube in operative relation to the reducing elements during withdrawal of said mandrel. 46. In a tube reducing apparatus, reducing elements for receiving a tube therebetween, means for feeding the tube forwardly, means between said feeding means and said elements for supporting said tube, a mandrel entering said tube and cooperating with said reducing elements, means for withdrawing the mandrel from said tube while the latter is partially completed and in engagement with said supporting means and for returning said mandrel to its initial position, and means for bringing a new tube into position between said mandrel and said supporting means while said mandrel is withdrawn. 47. In the art of reducing tubing, the method which comprises continuously reciprocating a carriage containing tube reducing elements, clamping a tube against movement in either of opposite directions while said tube is in operative relation to said carriage, withdrawing a mandrel from said tube, inserting a new tube between said mandrel and the first tube, and projecting said mandrel forwardly through said new tube and into said previously inserted tube. JAMES ROBERT COE.
